UNITED STATES PATENT OFFICE.

ETHAN I. DODDS, OF CENTRAL VALLEY, NEW YORK, ASSIGNOR TO FLANNERY BOLT COMPANY, OF PITTSBURGH, PENNSYLVANIA.

STAY-BOLT STRUCTURE.

1,403,746.

Specification of Letters Patent. Patented Jan. 17, 1922.

Application filed February 16, 1921. Serial No. 445,463.

To all whom it may concern:

Be it known that I, ETHAN I. DODDS, a citizen of the United States, and a resident of Central Valley, in the county of Orange and State of New York, have invented certain new and useful Improvements in Stay-Bolt Structures; and I do hereby declare the following to be a full, clear, and exact description of the invention, such as will enable others skilled in the art to which it appertains to make and use the same.

My invention relates to an improvement in stay bolt structures the object being to provide simple, comparatively inexpensive and easily assembled means for connecting the stay bolt to the outer sheet of the boiler, the construction being such that the stay bolt will be capable of universal movement on said connecting device, and it consists in the parts and combination of parts as will be more fully explained and pointed out in the claims.

In the accompanying drawings, Figure 1 is a view in longitudinal section through the head or outer end of a stay bolt and its support; Figure 2 is a similar view at right angles thereto, the cap being omitted, and Figures 3 and 4 are views similar to Figures 1 and 2 of a solid cap permanently closing the bolt opening and covering and concealing the bolt, and Figure 5 is a view in cross section of the cap shown in Figs. 3 and 4.

5 represents the outer sheet of a boiler provided with a bolt opening 6 therein. 35 This opening may be of any shape, and may be the threaded opening from which the sleeve of the ordinary Tate stay bolt has been removed. The shape of the opening is immaterial as the securing or supporting devices are located on and supported by the outer surface of the outer sheet instead of by the walls of the openings.

7 represents the bolt provided at its outer end with an eye 8 for the passage of the 45 supporting bar or bridge 9 the free ends of which are supported on the outer surface of the sheet 5. This bridge may be straight, but I prefer to bow it as shown so as to provide a recessed seat for the cross bar 10 of the eye of the bolt 7. The said cross bar 10 of the eye of the bolt is preferably elliptical in cross section as shown in Figure 1, and the bridge convex on its upper face in cross section as shown in Figure 2 so as to

permit the bolt to have a universal swinging movement on the bridge, and the eye 8 of the bolt is of greater depth than the bridge so that the bolt may move longitudinally thereon under collapsing stresses of the boiler sheets. 55

Secured to the outer surface of the sheet 5 preferably by welding as at 11, is the cylinder sleeve 12, the internal diameter of which is approximately the length of the bridge 9 so as to prevent any undue end-wise movement of the latter, or movement sufficient to permit either end of the bridge to drop into the bolt hole 6. This sleeve therefore holds the bridge in place, and is provided with a cap 13 which not only 70 closes the sleeve but the cap thereof forms an abutment for the bolt in the event of undue collapsing stresses on the boiler sheets which would tend to move the bolt outwardly. The sleeve is preferably counterbored and threaded as shown to receive the cap and is provided with a seat 14 on which the flange of the cap rests to form a steam tight joint. 75

With this construction there is no counterboring, threading or curving of the wall 80 of the bolt opening in the boiler sheet to receive the bolt bearing member, hence the cost of construction and assembling is greatly cheapened and simplified.

In applying the bolt, the bridge is inserted in the eye of the bolt and the latter passed through the bolt hole 6 and its inner end entered in the hole in the inner sheet (not shown) and screwed or driven there in the usual and well known manner, so that 85 the bolt will be solidly seated on the bridge. After or before the bolt has been secured as above explained the sleeve 12 is applied and secured to the outer sheet and the sleeve is then closed by the cap which may be removed at any time to permit of the inspection of the bolt.

The construction shown in Figures 3 and 4 is substantially identical with that shown in Figures 1 and 2, except that the cover 13* 100 is made solid and without a removable cap, and is permanently secured to the sheet.

In the construction shown in Figures 1 and 2 the sleeve 12 is recessed as at 15 at diametrically opposite points to receive the 105 ends of the bridge 9 whereby the latter will be prevented from turning.

In the construction shown in Figures 3,

4 and 5 the cover 13^a is offset as clearly shown at 15^a Figures 3 and 5 to receive the ends of the cross bar or bridge 9. In both forms a wrench or other tool can be applied 5 to the sleeve 12 or cover 13^a for turning the bolt to secure it to the inner sheet.

Having fully-described my invention what I claim as new and desire to secure by Letters-Patent, is:—

- 10 1. In a staybolt construction, the combination with a boiler sheet having a bolt opening therethrough a bridge mounted at its ends on the outer surface of said sheet, a bolt having an eye through which said bridge passes, the bolt being mounted on the bridge for universal movement and a cover for the bolt opening and so located with relation to the bridge as to limit the endwise movement of the latter.
- 15 2. In a stay bolt construction, the combination of a boiler sheet having a bolt opening therein, a bridge supported at its ends on the outer face of the sheet, a sleeve secured to the sheet and so located with relation to the bridge to limit the endwise movement of the latter, a bolt having an eye through which

the bridge passes and a cover detachably secured to the sleeve.

3. In a stay bolt construction, the combination of a boiler sheet having a bolt opening therein, a curved or bowed bridge spanning said opening and supported at its ends on the outer face of the sheet, a sleeve secured to the sheet around the said opening, a bolt having an eye through which the bridge passes and a detachable cover for said sleeve.

4. In staybolt construction, the combination of a boiler sheet having a bolt opening therethrough, a bridge mounted at its ends on said sheet, a bolt having an eye through which said bridge passes, the bolt being mounted on the bridge for universal movement and a cover for the bolt opening, the said cover being provided in inner face at opposite points with recesses to receive the two ends of the bridge.

In testimony whereof I have signed this specification in the presence of a subscribing witness.

ETHAN I. DODDS.

Witness:

EDWIN S. RYCE.
